US00D865689S

(12) **United States Design Patent** (10) **Patent No.:** **US D865,689 S**
Wang et al. (45) **Date of Patent:** **** Nov. 5, 2019**

(54) **ELECTRICAL MODULE**

(71) Applicants: **Microduino Inc.**, Westlake Village, CA (US); **Meike Technology (Beijing) Ltd.**, Beijing (CN)

(72) Inventors: **Zhenshan Wang**, Westlake Village, CA (US); **Kejia Pan**, Westlake Village, CA (US); **Bin Feng**, Westlake Village, CA (US)

(73) Assignee: **MICRODUINO INC.**, Beijing (CN)

(**) Term: **15 Years**

(21) Appl. No.: **29/624,178**

(22) Filed: **Oct. 30, 2017**

Related U.S. Application Data

(60) Division of application No. 29/536,822, filed on Aug. 19, 2015, now abandoned, which is a continuation-in-part of application No. 14/721,341, filed on May 26, 2015, now Pat. No. 9,801,300.

CLAIM

The ornamental design for electrical module, as shown and described.

DESCRIPTION

FIG. 1 is a top perspective view of an electrical module in accordance with the present invention;

FIG. 2 is a bottom perspective view of the electrical module shown in FIG. 1;

FIG. 3 is a top view of the electrical module shown in FIG. 1;

FIG. 4 is a bottom view of the electrical module shown in FIG. 1;

FIG. 5 is a left side view of the electrical module shown in FIG. 1;

FIG. 6 is a right side view of the electrical module shown in FIG. 1;

(Continued)

FIG. 7 is a front view of the electrical module shown in FIG. 1; and, FIG. 8 is a back view of the electrical module shown in FIG. 1.

1 Claim, 4 Drawing Sheets
